UNITED STATES PATENT OFFICE

98,858

DESIGN FOR A CHOCOLATE BAR

Curtis H. Gager, Scarsdale, N. Y., assignor to Walter Baker & Company, Inc., New York,
N. Y., a corporation of Massachusetts

Application July 24, 1935, Serial No. 57,793

Term of patent 14 years

To all whom it may concern:

Be it known that I, Curtis H. Gager, a citizen of the United States, residing at Scarsdale, county of Westchester, State of New York, have invented a new, original, and ornamental Design for a Chocolate Bar, of which the following is a specification, reference being had to the accompanying drawing, forming part thereof.

The figure is a perspective view of a chocolate bar showing the design.

I claim:

The ornamental design for a chocolate bar, as shown.

CURTIS H. GAGER.
